UNITED STATES PATENT OFFICE.

HENRY G. VOIGHT, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

LOCK ATTACHMENT.

No. 900,620.

Specification of Letters Patent.

Patented Oct. 6, 1908.

Application filed February 21, 1908. Serial No. 417,017.

To all whom it may concern:

Be it known that I, HENRY G. VOIGHT, a citizen of the United States, residing at New Britain, county of Hartford, Connecticut, 5 have invented certain new and useful Improvements in Lock Attachments, of which the following is a full, clear, and exact description.

My invention relates to certain new and 10 useful improvements in locks, the object being to provide a simplified construction for attaching the lock in place on the door, although incidentally there are other advantages which will be understood from a reading of the following description:

In the accompanying drawings, Figure 1 is 15 an edge elevation of a door fitted with my improved lock construction, said view being partly in section. Fig. 2 is a side elevation 20 of a portion of a door showing the mortise opening and illustrating by solid and dotted lines the lock case on the opposite side. Fig. 3 is an elevation of a detached detail.

A represents a stile of a door.

B represents a lock case containing therein 25 any suitable lock mechanism whereby the latch bolt or bolts may be operated through the medium of knobs, or keys, or both as desired.

Since the invention depends in no way 30 upon the special form of lock mechanism, it is unnecessary to describe the same herein.

C represents a back plate at the rear of the lock case B, the same being suitably secured 35 thereto and adapted to close in or cover the works. This plate has two rearwardly extending annular bosses C' C'', each of which has its internal wall threaded.

D is an escutcheon plate arranged to stand 40 on the opposite side of the door from the lock case. This escutcheon plate is preferably provided at its rear side with the annular bosses D' D''. A passage through the door stile is formed of a suitable size and outline 45 to receive the aforesaid bosses C' C'' D' D''. These bosses, when the parts are in place, are arranged to line up in pairs, C' with D' and C'' with D''.

E is a tubular coupling having a flanged 50 portion E' arranged to stand outside of the escutcheon plate D, while the tubular portion passes through the boss D' and threads into the boss C'. A similar tubular coupling is preferably provided for the other set of 55 bosses C'' and D''. The central passage

through the flange E' may be notched at its edge as indicated at E'', Fig. 3, so that a powerful wrench of special form may be employed to screw up each coupling to firmly clamp the door stile A between the case B 60 and the escutcheon D. In the form shown, F is a rose plate shown as standing upon the flange E', the edge of said rose plate over-standing and hiding notches E'' from view.

G conventionally represents a cylinder 65 lock, the cylinder case of which is made sufficiently long to pass into the tubular coupling E and engage with a reduced threaded portion B' in the lock case, and so that the roll back or equivalent device G' will stand in the 70 proper position to operate. In this instance this reduced portion B' into which the threaded end of the cylinder lock case G is screwed is concentric with the annular boss C' and is sufficiently smaller than said boss 75 C' to permit the forming of effective threads. When the cylinder lock is screwed into place, the usual set-screw H is set up in the usual manner to prevent the removal or displacement of the cylinder lock. A similar cylinder lock may be passed through the other 80 set of bosses or indeed dummies may be substituted in place of one or both of said cylinder locks, they serving as closures for the otherwise open end of the tubular couplings 85 E. By making the mortise of sufficient length to receive both sets of bosses, and also so as to provide a snug fit, great rigidity may be given to the lock parts, great resistance being afforded by the large tubular connections between the same, which tubular connections thus perform the double function of 90 affording a connecting means and a passage way for a cylinder lock or other operating mechanism as desired.

I represent the usual knob shanks, which 95 in this instance are in alinement.

J is a knob spindle passing through the opening in the door stile. While the preferable construction includes the annular 100 bosses on both the escutcheon plate and lock case, obviously good results may be attained if said bosses were omitted from the escutcheon since the powerful tubular couplings afford a broad support and serve to hold the 105 parts in proper alinement as well as in tight contact with the door stile. The annular bosses at the rear of the lock case may project rearwardly as far as desired to afford whatever range of adjustment is needed for 110

doors of different thicknesses. It would be possible, of course, to reduce the inner end of each tubular coupling and thread the same to receive the threaded inner end of the cylinder lock instead of attaching the latter directly to the reduced part B'. While this latter form is manifestly preferable, this, and other changes may be made without departing from the spirit and scope of my invention.

10 The tubular connecting member by which the lock is secured to one side of the door gives access to said lock from the other side of the door, whenever it is desired to employ operating mechanism to pass therethrough. 15 This is of particular utility in connection with fire doors, which ordinarily have metal lining, because the tubular wall through which access to the lock is had from the opposite side of the door furnishes a protecting means against flames, which under some conditions might attack the wood-work within the mortise.

It will be observed that the parts B and D operate as clamping members to engage 25 against the opposite sides of a door stile, so as to firmly hold the same between them. It will also be observed that the arrangement herein disclosed provides a correctly aligned 30 passage from one side of the door to the other to receive a lock-operating device accessible at one side and passing through and adapted to engage lock mechanism on the opposite side. This is of particular utility when one of the clamping members is a lock case.

35 What I claim is:

1. In a device of the character described, a case adapted to one side of a door, an escutcheon adapted to the other side of said door, an annular threaded boss projecting 40 rearwardly from the case, a flanged sleeve passing through said escutcheon, engaging the same and being screw-threaded at its inner end to connect with the threaded boss on said case, and a passage into said case in line with said sleeve-like connection.

2. In a device of the character described, a case adapted to one side of a door, an escutcheon adapted to the other side of said door, an annular threaded boss carried by the 50 case at its rear, an annular boss carried by

said escutcheon plate at its rear, a tubular coupling arranged to engage the said escutcheon passing through said boss thereon and screw-threaded at its inner end to engage the screw-threaded boss on the case.

55

3. In a lock, a lock case adapted to one side of a door, an escutcheon plate adapted to the other side of said door, two sets of annular bosses, one member of each set being threaded and carried by the lock case, the other member of each set being carried by the escutcheon, two tubular couplings flanged at the outer ends and passing through the bosses on the escutcheon plate, and threaded at their inner ends to engage with the threaded bosses on the case.

4. In a lock, a case adapted to one side of a door, an escutcheon adapted to the other side, an annular threaded boss carried by the lock case at its rear, an annular boss carried by said escutcheon plate at its rear, a tubular coupling arranged to engage the said escutcheon passing through said boss thereon and screw-threaded at its inner end to engage the screw-threaded boss on the case, a central reduced threaded opening into the case in line with the passage through said coupling.

70

5. In a lock, a lock case, an escutcheon plate, a threaded annular boss carried by and projecting to the rear of said case, a reduced and threaded opening into said case within said boss, an escutcheon plate and a tubular coupling threaded at one end to engage in the aforesaid boss, and means carried thereby at 75 its other end to engage said escutcheon plate.

80

6. In a door lock, a case arranged to be carried at one side of the door, a coupling member comprising a tubular device threaded at one end and provided with a clamping shoulder toward its other end, said lock case having an opening and a threaded wall surrounding the same, arranged to receive the threaded end of said coupling or connecting member.

90

HENRY G. VOIGHT.
